[57] CLAIM

The ornamental design for a hand-held bingo flag, as shown and described.

DESCRIPTION

FIG. 1 is a front elevational view of the hand-held bingo flag showing our new design with the cross-hatch pattern on the panels representing a conventional fabric;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.
